ATTORNEY.

UNITED STATES PATENT OFFICE

2,167,021

VELOCIPED

Bert J. Anderson, Hammond, Ind.

Application February 1, 1937, Serial No. 123,501

2 Claims. (Cl. 280—282)

This invention relates to an improved velocipede construction and has for one of its principal objects the provision of means for producing a light and sturdy stamped metal frame which 5 combines the favorable characteristics of both tubular and stamped vehicles.

Another important object of advantage resides in the provision of means for forming a backbone of two complementary parts without welding or riveting.

Still another important object of advantage resides in the provision of means for crimping the edges of one portion of the frame over the edges of the other portion.

15 A still further object of importance and advantage is the provision of means for securing a platform or deck plate to the backbone.

Additional objects of importance and advantage will become apparent as the following detailed description progresses reference being had 20 to the accompanying drawing, wherein—

Fig. 1 is a side elevational view of the backbone which embodies the invention.

Fig. 2 is a top plan view thereof.

25 Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a section, slightly enlarged, taken on line 6—6 of Fig. 1.

30 As shown in the drawing:

The reference numeral 10 indicates generally the backbone of this invention. In the preferred embodiment of the invention as is shown in the drawing the backbone is formed of two complementary stampings 12 and 14.

35 Formed of the upper edge of each stamping is a flange or fin which extends substantially the entire length thereof. The fin portion of each stamping preferably follows the curvature of the head and thence extends along the bottom of the stamping to a point intermediate the ends thereof. The fin or flange on the stamping 12 is indicated by the reference numeral 16 and the fin on stamping 14 is indicated by the reference 40 numeral 18.

The fin 16 is substantially twice the width of fin 18. When the two stampings 12 and 14 are brought together the fin 16 is crimped over the fin 18, as is best shown in Figs. 3 and 4, to permanently secure the stampings together.

45 Formed in the frame near the front thereof is an opening 20 which is adapted to receive a bushing or a steering post.

Formed in the backbone intermediate the ends 50 thereof is a seat post receiving opening 22. An

aperture 24 is provided in one of the stampings in alignment with the opening 22. The opening 24 provides access for means for adjustably securing a seat post in position.

A portion of the metal of each stamping 5 between the openings 20 and 22 is cut away and the horizontal edges 26 are turned inwardly to form two substantially tubular portions as is best shown in Figs. 1 and 3. The vertical edges 27 of the cut away portion of one stamping overlap and 10 are secured to corresponding portions of the other stamping. This construction in addition to greatly enhancing the appearance of the finished frame also provides a flexibility and sturdiness 15 which is not attainable in solid construction.

The rear end of each stamping is bifurcated and the portions thereof are indicated by the reference numerals 28 and 30. The portions 28 are curled into substantially tubular formation and each portion 30 is semi-circular in cross section as is best shown in Fig. 4. In assembly a cross section of the rear part of the frame shows the component member thereof in spaced apart triangular formation.

Formed adjacent the rear end of each portion 25 of the backbone is an annular shoulder 32. The shoulder 32 is preferably formed by bulging a portion of the metal as is best shown in Fig. 6. However, it will be apparent that a shoulder may be formed on the member in any conventional 30 manner.

When the improved backbone of this invention is assembled with a platform or rear frame member 33, the ends 34 are inserted through openings in such rear frame member. The ends 34 are 35 then spread or clinched against the bottom surface of the rear frame member 33 and the annular shoulders 32 are drawn tightly against the upper surface.

It will be apparent from the foregoing that 40 herein is provided an improved backbone structure which is sturdy and rugged and which may be economically produced.

Moreover, the device of this invention is 45 clinched throughout and therefore entirely dispenses with the conventional and expensive means, such as welding or riveting, of securing the parts together or of attaching the assembled unit to a rear frame member.

I am aware that many changes may be made 50 and numerous details of construction varied throughout a wide range without departing from the principles of this invention and I, therefore, do not propose limiting the patent granted herein on other than is necessitated by the prior art. 55

I claim as my invention:

1. A backbone comprising a pair of complementary stampings, the rear end of each stamping being bifurcated, one bifurcated portion of each stamping being curled into tubular formation, and means for securing said stampings together.

2. A backbone comprising a pair of comple-

mentary stampings, the rear end of each stamping being bifurcated, one bifurcated portion of each stamping being curled into tubular formation, means for securing said stampings together, and means for attaching a platform to the rear end of the backbone.

BERT J. ANDERSON.
